UNITED STATES PATENT OFFICE.

WILLIAM MURPHY, OF ST. JOHN, NEW BRUNSWICK, CANADA.

OCTAVE-COUPLER FOR ORGANS.

SPECIFICATION forming part of Letters Patent No. 336,134, dated February 16, 1886.

Application filed September 3, 1885. Serial No. 176,097. (No model.)

To all whom it may concern:

Be it known that I, WILLIAM MURPHY, a subject of the Queen of Great Britain, residing at St. John, in the county of St. John and 5 Province of New Brunswick, Canada, have invented a new and useful Improvement in Octave-Couplers for Organs, of which the following is a specification, reference being had to the accompanying drawings.

10 My invention relates to an improvement in octave-couplers for organs; and it consists in the peculiar construction and combination of devices, that will be more fully set forth hereinafter, and particularly pointed out in the 15 claims.

In the drawings, Figure 1 is a perspective view of parts of an organ-action embodying my improvements. Fig. 2 is a vertical section taken in the direction of the length of the 20 keys. Fig. 3 is a rear elevation. Figs. 4 and 5 are enlarged detail views of my improved form of hinge to journal the tracker-rods to the hinged board. Fig. 6 is a diagram illustrating the movement of one of the tracker-pin rods 25 out of engagement with one of the key buttons.

A represents a portion of the organ-case, and B is the key-frame of the same.

In the illustration enough only of an organ is shown to fully illustrate my improvements, 30 as the manner of applying them will be readily understood by persons skilled in the art of organ-building.

C' designate the pitman-frames, in which the pitmen D work in perforations made for 35 them. Each pitman D is provided near its lower end with a button, D'. The upper ends of the pitmen D enter eyes in buttons D'', secured to the under faces of the key-levers E. These buttons D'' are prevented from turning 40 on their pivots by small brace-wires D', entering the sides of the buttons D'' and the under faces of the key-levers E.

No claim is made herein to this construction of the buttons on the key-levers, as it 45 forms no part of this present invention, being claimed in Letters Patent of the United States No. 322,121, granted to me July 14, 1885.

F designates a hinged or pivoted (preferably diamond-shaped) board, which is shown 50 arranged in the rear of the pitman-frames in this instance. To the face of the board F

farthest from the pitman-frames C C' the double tracker-pin rods H are secured in bearings H'. The tracker-pin rods have the points of their arms H³ at their lower ends flattened, 55 and these flattened ends rest upon the buttons or collars D' near the lower end of the tracker-pins or pitmen D. The upper ends of the tracker-pin rods have horizontally - curved arms H², which extend over the upper pitman-board and have their laterally-curved ends engage the under faces of the buttons D'' on the under faces of the key-levers, when the board F is vertical, as shown in solid lines in Figs. 2 and 6. When the board F is inclined 60 toward the tracker-pins, in the position shown in dotted lines in the said figure, the curved upper ends of the tracker-pin rods are moved forwardly, as shown in dotted lines in Figs. 2 and 6, out of engagement with the buttons 65 under the key-levers, and the latter can be played upon without affecting the tracker-pin rods. The upper edge of the board F is connected to a sliding arm, F², which extends back in rear of the keys. The front side of 70 the board F is beveled on its upper and lower edges, as at f, in order to enable said board to be inclined in the direction of the tracker-pins, as before described, and the tracker-pin rods are journaled to this board by means of 75 bearing-plates L and L', which are secured on the beveled edges of the boards by means of screws or rivets. These plates are formed of pieces of sheet-brass or other suitable material, and the edges of these plates that project beyond the edges of the board are notched, 80 as at a, leaving intervening tongues, b, which are inclined to correspond with the inclination of the tracker-pin rods, being at right angles thereto, and the outer ends of the 85 tongues are bent rearwardly about three-fourths around the tracker-pin rods to form bearings therefor. This manner of forming the bearings for the tracker-pin rods is advantageous over the mode in common practice 90 of journaling said rods separately, being much cheaper and more secure and firm. The pivotal lug l, for the attachment of the sliding arm, is formed with the bearing-plate L, and at the ends of the lower bearing-plate, L', are 95 formed bearings l', by means of which the board F is hinged or pivoted at its lower end 100

to the organ-action, as at F³. The inner sides of the bearings b are lined with felt bushing, as at d, to prevent metallic sounds. The lower ends of the tracker-pins rest upon the valves U, which are of the usual construction.

Having thus described my invention, I claim—

1. The combination, in an organ-action, of the hinged or pivoted board F, the tracker-pin rods, and the bearing-plates secured to the board, and having the tongues bent around the tracker-pin rods to form journals or bearings therefor, substantially as described.

2. The combination, in an organ-action, of the hinged or pivoted board F, the tracker-pin rods, and the bearing-plates secured to the board, and having the tongues bent around the tracker-pin rods to form bearings therefor, one of said bearing-plates having the bearings 15 formed with it to hinge or pivot the board, substantially as described.

3. The combination, in an organ-action, of the hinged or pivoted board F, the sliding

rod for operating said board, the tracker-pin rods, and the bearing-plates secured to the board, and having the tongues bent around the tracker-pin rods to form bearings therefor, one of said bearing-plates having the pivotal lug l for the attachment of the sliding rod, substantially as described.

4. The bearing-plates having the tongues bent to form bearings for the tracker-pin rods, substantially as described.

5. The bearing plates having the tongues bent to form bearings for the tracker-pin rods, 35 and the bushing in said bearings surrounding the tracker-pin rods to prevent metallic sounds from the latter, substantially as described.

In testimony that I claim the foregoing as my own I have hereto affixed my signature in presence of two witnesses.

WILLIAM MURPHY.
